(57) **CLAIM**

We claim the ornamental design for an optical sighting device for carbines and other projectile weapons, as shown and described.

DESCRIPTION

FIG. 1 is a front perspective view of an optical sighting device for carbines and other projectile weapons.

FIG. 2 is a rear perspective view of the optical sighting device for carbines and other projectile weapons of FIG. 1.

FIG. 3 is a front elevation view of the optical sighting device for carbines and other projectile weapons of FIG. 1.

FIG. 4 is a rear elevation view of the optical sighting device for carbines and other projectile weapons of FIG. 1.

FIG. 5 is a right-side elevation view of the optical sighting device for carbines and other projectile weapons of FIG. 1.

FIG. 6 is a left-side elevation view of the optical sighting device for carbines and other projectile weapons of FIG. 1.

FIG. 7 is a top plan view of the optical sighting device for carbines and other projectile weapons of FIG. 1; and,

FIG. 8 is a bottom plan view of the optical sighting device for carbines and other projectile weapons of FIG. 1.
